TWO-STROKE CYCLE, INJECTION-TYPE INTERNAL-COMBUSTION ENGINE

Andreas Scheiterlein, Graz, Austria, assignor to Gustav Ospelt, Vaduz, Liechtenstein

Application December 29, 1952, Serial No. 328,383

Claims priority, application Austria January 19, 1952

2 Claims. (Cl. 123—195)

The present invention relates to two-stroke cycle, injection-type internal-combustion engines with upright cylinders arranged in a row and piston-controlled intake and exhaust ports.

It is known to arrange in engines of this type the accessories driven by a V belt from the front end of the engine, such as the scavenging and charging blower, the dynamo, and the cooling water pump and, furthermore, the oil cooler and the exhaust manifold, at the two longitudinal sides of the engine, with their axes extending in the direction of the crankshaft axis. The devices in drive connection with the engine by gears, such as the injection pump and the starter, are usually mounted on an end wall beside the flywheel, with their axes also extending in the direction of the crankshaft axis.

In these known arrangements the engine housing is provided with mounting surfaces for the parts and members of the engine to be attached laterally of the row of cylinders, and these mounting surfaces are adapted in shape and position to these parts and members to be attached. Machining these differently situated mounting surfaces is a time consuming and expensive operation. Moreover, an overlap of these surfaces must be avoided so that the space requirement in most cases is larger than would correspond to the size of the parts or members to be attached. Particularly in low-power engines the poor space utilization is of detrimental effect because the external walls available for the attachment of the accessories or auxiliaries and the like are relatively small whereas the size of these accessories is not reduced for a smaller power in the same proportion as the size of the engine.

The invention has as its object to avoid these disadvantages and essentially resides in the fact that all connection surfaces of the engine housing for the engine members and parts attached laterally to the engine housing are situated in two downwardly diverging planes on both sides of the row of cylinders, and that the scavenging blower and all other accessories or the like driven from the crankshaft by a V belt or the like at the front end of the engine, as well as the oil cooler and the exhaust manifold, are attached to these connecting surfaces with their axes parallel to the crankshaft axis.

Since all connecting surfaces on either side of the engine housing extend in one plane, machining them is facilitated substantially. By the downwardly diverging arrangement of these planes which are to be machined at both sides of the engine housing the original or fundamental shape of the engine is taken into account to a great extent. The space from the cylinders to the crankcase may be utilized for the connection of the various parts, organs and accessories of the engine. Since all connecting surfaces on one side of the engine lie in one plane, a space-saving arrangement of the parts, members and accessories of the engine is possible. This is of decisive importance particularly for low-power engines, in which the surface area available for the arrangement of

the accessories is relatively small. Hence, the invention relates more particularly to engines having a displacement of less than 1.0 litres per cylinder.

The invention affords special advantages in two-stroke cycle injection-type internal-combustion engine with reverse scavenging and a displacement of less than 1 litre per cylinder. Since in such machines with reverse scavenging the exhaust manifold and the scavenging blower must be arranged one below the other on the same side of the row of cylinders and in such small engines the distance between the exhaust manifold and scavenging blower must be relatively small, the arrangement of the connecting surfaces for these parts in one plane has special advantages in that case. For this reason such small two-stroke-cycle, injection-type internal-combustion engines with reverse scavenging have arranged according to the invention the exhaust manifold on the intake and exhaust side, at the level of the exhaust ports, whereas the scavenging blower is arranged below the exhaust manifold and the starter is arranged below the scavenging blower, while on the other side the fuel-injection pump is situated approximately at the level of the exhaust manifold, and the dynamo and the cooling water pump are situated axially one behind the other below the injection pump whereas the oil cooler is situated below the dynamo and the cooling water pump.

In the drawing the invention is illustrated schematically with reference to an example.

Fig. 1 is a cross-sectional view of the engine, taken along line I—I of Fig. 3.

Fig. 2 is an elevation of the engine according to Fig. 1, seen from the left.

Fig. 3 is an elevation of the engine according to Fig. 1, seen from the right.

35 In the two-stroke cycle, injection-type internal-combustion engine represented in the drawing, 1 is the engine housing, 2 and 3 are the cylinder heads, 4 the cylinder liners fixed to the cylinder heads by screws, which are not shown, 5 are the pistons, 6 is the connecting rod, 7 the crankshaft, and 8 the bearing bracket of a crankshaft bearing. The underside of the engine housing 1 is shut off by an oil sump 9.

The cylinder heads 2 and 3 have inserted combustion chambers 10, into each of which an injection nozzle 12 discharges, which is inserted into a screw body 11.

On both sides of the row of cylinders the engine housing 1 has mounting surfaces for the various parts, members and accessories of the engine, which surfaces lie all in two downwardly diverging planes 13 and 14.

50 On the left-hand side of the engine the dynamo 15 with the cooling water pump 16 and the oil cooler 17, and on the right-hand side of the engine the exhaust manifold 19 and a Roots blower 18 are connected with their axes parallel to the crankshaft axis to these mounting surfaces. The axis of the cooling water pump and of the dynamo is designated with 49, the axis of the oil cooler with 53, the axis of the exhaust manifold with 52 and the axis of the Roots blower with 51, whereas the crankshaft axis is indicated at 48.

55 The dynamo 15 and cooling water pump 16 are arranged on a base plate 20 and thereby secured to the side of the motor housing. The securing surface lying in plane 13 is exteriorly bounded by the contour of base plate 20 and interiorly by dotted line 21 (Fig. 2). The oil cooler 17 located directly beneath this assembly is secured on securing surfaces 22 lying also in plane 13, one disposed forwardly and the other rearwardly. The connection of the cooling water pump 16 with oil cooler 17 is a short curved pipe 23.

60 The exhaust manifold 19 arranged on the other motor side (right-hand side of Fig. 1) is at the level of the exhaust slots 24, 25 (Figs. 1 and 3) provided in motor

housing 1 and is connected by flanges to the machined attaching surfaces 26 and 27 (Fig. 3) located in plane 14. For reasons of a favorable utilization of space, the exhaust manifold has an inner cross section lying so high that its lowest point lies at the same level with the lower edge of the exhaust slot 24. The Roots blower 18 is also mounted in plane 14, the contour of the attaching surface being shown in dotted lines in Fig. 3 and designated by 50.

The drive of the mentioned accessories 15, 16, 18 is carried out from the front side of the motor in a known manner by wedge belts. The pulley 28 keyed on crank shaft 7 drives by means of the single wedge belt 29 simultaneously through pulley 30 dynamo 15 and through pulley 31 fan wheel 32. Two additional wedge belts 33 trained over pulley 28 drive through a pulley 34 the Roots blower 18.

Starter 35 and fuel injection pump 36 are fastened on the walls 38 and 39 respectively of the cover plate 37 located on the flywheel side and have their drive shafts 40 and 41 respectively parallel to axis 48 of crankshaft 7. Starter 35 is connected by pinion 42, shown in Fig. 3 by dotted lines in retracted position, with the gear teeth 44 fixed to the flywheel (not shown) in operating position. The injection pump 36 is driven from crankshaft 7 by a gearing arranged on the flywheel side of the motor. A gear 45 keyed to the crankshaft drives through an intermediate gear 46 a gear 47 of the size of gear 45 and keyed to drive shaft 41 of the injection pump.

I claim:

1. Two cycle injection internal combustion engine with cylinders arranged in a row comprising a one-piece housing, a crank shaft journaled in the lower housing part constituting a crank case and below the cylinders, liners for the cylinders inserted in the housing and having intake and exhaust ports, pistons each controlling the ports of a cylinder, cylinder heads fixed to the top of the hous-

ing, the housing including lengthwise side walls with outer coplanar attaching surfaces and downwardly diverging, accessories each attached to an attaching surface and including a cooling water pump, a dynamo, a scavenging blower, an oil cooler, and an exhaust manifold, the axes of the accessories being disposed parallel to the crank shaft, the dynamo, water pump and scavenging blower being belt-driven from the crank shaft, a flywheel carried by the crank shaft adjacent an end of the housing, a cover closing the housing end adjacent the flywheel, and other accessories attached to the cover plate and including a starter, a fuel injection pump, said other accessories having their axes parallel to the crank shaft, and gearing connecting the other accessories to the crank shaft.

2. The engine according to claim 1 and also comprising reverse scavenging means and wherein the stroke volume is less than one liter per cylinder and wherein the exhaust manifold is located on one side of the housing substantially at the level of the intake and exhaust ports and the scavenging blower is located below the exhaust manifold and the starter is located below the scavenging blower, the fuel injection pump being located on the other side of the housing at about the level of the exhaust manifold and below the manifold the dynamo and cooling water pump in axial alignment and below the cooling water pump and dynamo, the oil cooler.
